COPYHOLDER

Ralph V. Streeter, St. Paul, Minn.

Application August 27, 1934, Serial No. 741,644

6 Claims. (Cl. 120—32)

My invention relates to devices for holding a copy sheet and particularly to a device for successively bringing various portions of such a sheet into view.

5 It is an object of my invention to provide a novel, compact copy holding device capable of being conveniently operated to successively bring into view lines of written or typewritten matter on a sheet.

10. Another object is to provide such a device having a sheet carrying roller in which means is provided for gripping one end of a sheet.

Still another object is to provide such a device having key operated means for rotating the roller through a predetermined angle for each operation of the key wherein the roller is free for rotation when the key is in its normal position.

20. Yet another object is to provide such a device wherein all movement of the roller will be positively stopped at the termination of an operation regardless of how violently or how gently the operating means is manipulated.

A further object is to provide such a device including means for spotting lines of written or typewritten matter on a sheet and exerting a frictional drag on the sheet to keep the same tightly stretched about the periphery of the roller.

30 A still further object is to produce such a device of simple, rugged and inexpensive construction and adapted for use in close cooperation with a keyboard such as the keyboard of a linotype machine.

35 These and other objects and advantages of the invention will be more fully set forth in the following description made in connection with the accompanying drawing, in which like reference characters refer to similar parts throughout the several views, and in which:—

Fig. 1 is a top view of my copy holder;

Fig. 2 is a vertical transverse sectional view, drawn to an enlarged scale;

Fig. 3 is an end view with the end cover removed, drawn to a slightly enlarged scale and showing the operating mechanism in normal position:

Fig. 4 is a similar view to Fig. 3 except that the operating mechanism is shown in operated position, and

Fig. 5 is a perspective view of my copy holder, drawn to a reduced scale, in cooperative relation with the keyboard of a linotype machine.

55 Referring to the drawing, my copy holder includes a cylindrical roller 6, means for housing and revolvably supporting the roller, means for rotating the roller and means for attaching a sheet of paper to the roller.

60 A combined frame and housing is constructed as follows: A pair of similar, relatively heavy

end walls or plates 7 and 8, shaped as shown in Figs. 2, 3 and 4, are vertically disposed in parallel relation to each other spaced apart a distance slightly greater than the length of the roller 6. A front plate 9 extends between and is secured to the slightly curved front edges of the respective end plates 7 and 8 and a rear plate 10 extends between and is secured to the curved rear edges of the respective end plates 7 and 8. The front and rear plates 9 and 10 obviously rigidly maintain the end plates 7 and 8 in the relative positions thereof previously described.

At the respective ends of the roller 6, outwardly projecting shafts or journals 11 and 12 are formed integrally and coaxially with the roller 6. The shafts 11 and 12 are respectively journaled in substantially centrally located apertured portions of the end plates 7 and 8 with roller 6 disposed between the end plates 7 and 8 and between the front and rear plates 9 and 10. The end plates 7 and 8 are of such dimensions that the front and rear plates 9 and 10 are spaced from the periphery of the roller 6. The journal 11 projects a short distance outwardly of the end plate 7 for a purpose to be described and the journal 12 terminates substantially flush with the outer side of the end plate 8. A knob 13 is mounted on a small shaft 14 secured in an aperture in the shaft 12 in coaxial and outwardly extending relation to the shaft 12.

Between the upper edges of the front and rear plates 9 and 10 the upper portions of the end plates 7 and 8 are cut away to leave curved edges inclined for counterclockwise rotation of the curved periphery of the roller 6.

35
A step by step operating mechanism for rotating the roller 6 through successive equal predetermined angles is mounted on the end plate 7 and associated with the projecting portion of the shaft 11. A ratchet 15 is mounted on the projecting portion of the shaft 11 with its teeth suitably inclined for counterclockwise rotation of the ratchet as viewed in Figs. 3 and 4. 40

An operating lever 16 having a finger piece 16a formed on its free end is pivotally mounted at its rear or remaining end on a headed pivot screw 16b projecting outwardly from the lower rear

portion of the end plate 7. The lever 16 is located below the ratchet 15, is swingable in a vertical plane between an upwardly and forwardly extending normal position and a substantially

extending normal position and a substantially horizontal operated position. A stop screw 17 extending outwardly from the end plate 7 and having a compressible shock absorbing collar 17a thereon is suitably positioned to limit upward movement of the lever 16 as shown in Fig. 3. A second stop screw 18 extending outwardly from the end plate 7 is suitably positioned to limit downward movement of the lever 16 as shown in Fig. 4. Obviously, the stop screws 17 and 18

limit the movement of the lever 16 to movement within a fixed predetermined angle.

A lug 19 is integrally formed on the upper side of the lever 16 a short distance forwardly of the pivot screw 16b. A curved pawl 20 has a bifurcated lower end portion 20a placed on the lug 19 in straddling relation thereto. A pivot pin 21 extends through aligned apertures in the lug 19 and the bifurcated portion 20a of the pawl 20, so that the pawl 20 is mounted on the lever 16 for rearward and forward swinging movement relative thereto. The pawl 20 extends upwardly and somewhat rearwardly from the pivot pin 21 and at its upper end has a tooth 20b normally closely adjacent the toothed periphery of the ratchet 15 and adapted for engagement therewith.

A helical tension spring 22 is connected at its respective ends to a spring anchoring eye 20c formed on the upper end of the pawl 20 and a spring anchoring element 23 projecting from the outer side of the upper rear portion of the end plate 7. The spring anchoring element 23 is so located that the spring 22 will pull the pawl 20 and the lever 16 to their upper limits of movement and will normally hold the tooth 20b out of engagement with but closely adjacent to the ratchet 15 as shown in Fig. 3.

As the lever 16 is depressed against the tension of the spring 22 the pawl tooth 20b is brought into engagement with the ratchet 15 and completion of movement of the lever 16 toward its lower limit of movement results in the pawl 20 being drawn downwardly to rotate the ratchet 15 through an angle corresponding to the distance between adjacent teeth of the ratchet. An abutment element 20d is formed on the rear side of the pawl 20 for cooperation with a second abutment element 19a comprising the rear portion 35 of the upper side of the lug 19. The abutment elements 20d and 19a are arranged to abut each other as shown in Fig. 4 when the lever 16 reaches its lower limit of movement so as to then prevent rearward swinging of the pawl 20 relative to the lever 16. Restraint of the pawl 20 from rearward movement causes the tooth 20b of the pawl 20 to be positively retained in a position between two adjacent teeth of the ratchet 15 so as to positively prevent further rotation of the ratchet 50 15 after the lever 16 has reached its lower limit of movement even though the lever 16 has been swung downwardly with sufficient violence to store considerable energy in the roller 6.

When the lever 16 is released after an operation thereof the spring 22 returns the lever 16 and the pawl 20 to their normal positions shown in Fig. 3. The pawl 20, when in its normal position, is completely out of engagement with the ratchet 15 and hence the roller 6 is free for rotation by means of the knob 13 if desired.

Obviously the above described roller rotating mechanism positively limits the roller 6 to rotation through only a fixed predetermined angle for each operation of the lever 16 and, when the lever 16 is in its normal position, leaves the roller 6 free for rotation by means of the knob 13 through any desired angle.

A cover 24 of suitable shape and secured to the end plate 7 is provided to enclose the entire step by step roller operating mechanism except the finger piece 16a of the lever 16 and the lower stop screw 18. The cover 24, is, of course, suitably cut away to permit free movement of the lever 16.

At one portion of its periphery the roller 6 is

provided with means for holding one end of a sheet of paper which is wrapped about the periphery of the roller. At the portion referred to on its periphery the roller 6 is provided with a groove 25 of substantial width and depth and extending through the greater portion of the length of the roller parallel to the longitudinal axis of the roller. The ends of the groove 25 are stepped as at 25a so that the rear portion of the groove 25 (when the grooved portion of the roller 6 is uppermost) is slightly less in length than the front portion. A rock shaft 26 extends in and longitudinally of the groove 25 just forward of the step 25a and is journaled at its respective ends in apertures in the respective end portions of the roller beyond the ends of the groove 25. A clamping plate 27, lying in groove 25 and having a shape similar to but slightly smaller than the groove, is secured to the shaft 26 along a line parallel to and slightly rearwardly of the longitudinal center line of the plate 27 by means of ears 27a formed integrally with the plate 27 and bent to encircle the shaft 26. A helical torsion spring 28 is wound about the shaft 26 and anchored at its respective ends to the plate 27 and the portion of the roller 6 defining the bottom of the groove 25 so as to urge the forward portion of the clamping plate 27 toward the roller 6. Pressing the rear portion of the plate 27 toward the roller 6 will raise the forward portion thereof outwardly away from the roller 6 against the tension of the spring 28.

A block 29 of compressible material such as rubber is secured in the forward portion of the groove 25 with its outer face disposed just inwardly of the face of the roller 6 and positioned to register and cooperate with the forwardmost portion 27b of the clamping plate 27 to clamp the end of a sheet of paper P therebetween.

Means for frictionally engaging a sheet of paper disposed on the roller 6 and setting off or spotting a line of indicia such as written or type-written matter on the sheet is provided. A rod 30 extending parallel and closely adjacent to and just inwardly of the upper edge portion of the front plate 9 is journaled at its respective ends in suitable apertures in the end plates 7 and 8 for rocking movement therein. A rearwardly and upwardly curved guide plate 31 extending through substantially the entire distance between the end plates 7 and 8 is secured along its lower and forward edge to the rod 30. The upper and rear portion of the curved plate 31 bears against the periphery of the roller 6 or against a sheet of paper P wrapped about the roller 6 as shown in Fig. 2. A helical torsion spring 32 is wrapped about the medial portion of the rod 30 and bears at its respective ends against the guide plate 31 and the front plate 9 to urge the rear portion of the guide plate 31 toward the roller 6. An operating element or finger plate 33, formed integrally with the guide plate 31 extends substantially upwardly from the rod 30 for use in rocking the guide plate away from the roller 6.

The guide plate 31 functions to frictionally engage a sheet of paper P disposed on the roller 6 and to yieldingly restrain the sheet against movement with the roller 6 as the roller 6 is rotated thus keeping the sheet relatively tightly stretched over the periphery of the roller 6. The upper rear edge 31a of the guide plate 31 functions as a guide edge to set off or mark a line of written or typewritten matter on the sheet P.

The lower side of my device is suitably shaped to permit placing the device on a linotype ma-

chine just above and behind the keyboard K thereof as shown in Fig. 5, whereby the portion of a sheet P on the upper side of the roller 6 is clearly visible to the operator of the machine and 5 the finger piece 16a and knob 13 are conveniently accessible to the operator.

In normal use of my copy holding device the top marginal portion of a sheet upon which copy is written is clamped between the forward end 10 of the clamping plate 27 and the knob 13 is turned to rotate the roller 6. The roller 6 is turned through approximately one revolution to wrap the sheet around the roller 6 and bring the uppermost line of copy into a position just rearwardly of the guide edge 31a. The next following line of copy is obviously concealed from view by the guide plate 31 and the remaining lines of copy are concealed within the device. When the linotype operator has finished copying the 15 first line of copy he depresses and then releases the finger piece 16a to rotate the roller 6 through the predetermined angle previously referred to and thus brings the next line of copy out of concealment under the guide plate 31 into view immediately rearwardly of the guide edge 31a. This 20 procedure is repeated for each successive line of copy.

To remove the sheet from the device when all the matter thereon has been copied the knob 13 25 is manipulated to bring the roller 6 into the position shown in Fig. 2. Then by pressing the rear portion of the clamping plate 27 the sheet is released and may be withdrawn from the device. Depressing the finger plate 33 will raise 30 the guide plate 31 from engagement with the sheet and facilitate removal thereof from the device.

It is apparent that I have invented a novel and 35 simple copy holder adapted for close cooperation with a keyboard such as that of a linotype machine and capable of convenient and positive operation to bring into view one line of copy at a time. It is also apparent that my device is well adapted for use with keyboards other than those 40 of linotype machines and with equipment other than keyboards.

It will, of course, be understood that various 45 changes may be made in the form, details, proportions and arrangement of the parts, without departing from the scope of my invention, which generally stated, consists in a device capable of carrying out the objects above set forth and in the novel parts and combinations of parts disclosed and defined in the appended claims.

50 55 What is claimed is:—

1. In a copy holder, a revoluble member, a ratchet secured thereon, a pawl engageable with said ratchet, means for engaging said pawl with said ratchet and moving said pawl through a predetermined distance to rotate said ratchet through a predetermined angle and locking means rendered operative by said pawl moving means at completion of its movement for positively holding said pawl in engagement with said ratchet until said pawl moving means has been moved toward its initial position.

2. In a copy holder, a revoluble member, a ratchet secured thereon, a pawl engageable with said ratchet, means for engaging said pawl with said ratchet and moving said pawl through a

predetermined distance to rotate said ratchet through a predetermined angle and a pair of cooperating abutment elements one of which is located on said pawl, said abutment elements being arranged to abut each other when said pawl has been moved through said predetermined distance to hold said pawl in engagement with said ratchet until said pawl moving means has been moved toward its initial position. 5

3. In a copy holder, a revoluble member, a ratchet connected thereto, an operating lever mounted for swinging movement through a predetermined angle, a pawl connected with said lever and positioned for engagement with said ratchet as said lever is operated and to rotate 10 said ratchet as movement of said lever is completed, and a pair of abutment elements associated with said pawl and arranged to abut each other as movement of said lever is completed to hold said pawl in engagement with said ratchet 15 until said lever has been moved toward its unoperated position.

4. In a copy holder, a revoluble member, a ratchet connected thereto, an operating lever mounted for swinging movement through a predetermined angle, a pawl connected with said lever and positioned for engagement with said ratchet as said lever is operated and to rotate 20 said ratchet as movement of said lever is completed, and a pair of abutment elements one located on 25 said pawl and the other located on said lever, said abutment elements being arranged to abut each other as movement of said lever is completed to hold said pawl in engagement with said ratchet until said lever has been moved toward its unoperated position. 30

5. In a copy holder, a revoluble member, a ratchet secured thereon, an operating lever mounted for swinging movement between predetermined limits, a pawl swingably mounted on said lever and positioned and arranged for engagement with said ratchet as said lever is moved toward its operated position, yieldable means urging said pawl out of engagement with said ratchet and said lever toward its unoperated position, 40 and a pair of abutment elements located respectively on said pawl and said lever and arranged to abut each other as said lever approaches its operated position to hold said pawl in engagement with said ratchet until said lever has been 45 moved toward its unoperated position. 50

6. In a copy holder, a revoluble member, a ratchet secured thereon, an operating lever mounted for swinging movement between predetermined limits, a pawl swingably mounted on 55 the medial portion of said lever and extending away therefrom at substantially right angles in the plane in which said lever swings, said pawl being positioned for engagement with said ratchet, resilient means urging said pawl longitudinally 60 in a direction away from said lever and acting to normally maintain said lever in an initial position at one of its limits of movement and a pair of cooperating abutment elements respectively formed on said pawl and said lever and arranged to abut one another as said lever approaches its 65 operated position so as to hold said pawl in engagement with said ratchet until said lever has been moved toward its initial position.
